UNITED STATES PATENT OFFICE

2,419,176

VOLTAGE REGULATOR

George F. Starnes, Hickory, N. C.

Application August 30, 1943, Serial No. 500,530.

5 Claims. (Cl. 128—405)

1

This invention relates to a voltage regulator, and may be used in electrical circuits for regulating the voltage, or it may be used as an electro-therapeutic machine for treating a person who by manipulating the machine can control the amount of voltage which is allowed to pass through the body of the operator seizing the two handles of the apparatus.

It is an object of this invention to provide a voltage regulator which can be used in lighting circuits for houses and the like, or which can also be used in an electro-therapeutic machine, whereby a plurality of resistances such as incandescent bulbs are disposed in a circuit in parallel relation and by gradually disconnecting these bulbs, one at a time, from the circuit, the voltage in the circuit can be increased.

It is a further object of this invention to regulate the voltage in a circuit by placing a plurality of resistances therein, so that only a given flow of voltage can pass through the circuit, together with means for disconnecting a plurality of these resistances from the circuit to increase the voltage flowing through the circuit.

Some of the objects of the invention having been stated, other objects will appear as the description proceeds, when taken in connection with the accompanying drawings, in which:

Figure 1 is a top plan view of the apparatus;

Figure 2 is a side elevation of the apparatus;

Figure 3 is an enlarged detail view of the lower right-hand portion of Figure 2;

Figure 4 is a schematic wiring diagram of the apparatus.

Referring more specifically to the drawings, the numeral 10 indicates a base board having an upstanding back portion 11 and an upstanding front board 12. Secured in the front board 12 is a U-shaped pipe 13 in the legs of which there is slidably mounted a rod 14 with its reversely turned handle portion 14a. This rod is also slidably mounted in an upstanding block 15 on which a plurality of leaf spring contact members 16, 17, 18, 19, 20, and 21 are mounted, which are adapted to normally press against an upstanding metallic post 22 which is integral with rod 14. The rod 14 has pivotally secured thereto on bolt 23 an arm 24 of non-conducting or insulating material and on the free end of this arm 24, there is mounted a metallic member 25. This member 25 has pivotally secured on the free end thereof a metallic contact pin 26 which slidably penetrates the chute member 27 and bridges the coin slot 28 therein. The coin chute 27 has a fixed metallic pin 29 which bridges the slot 28.

2

The means for mounting the member 24 on the end of rod 14 by means of screw 23 is a friction joint and comprises the following: Immediately below the head of bolt 23, there is a metallic washer 30 and below that a fiber or friction washer 31 and below the rod 14 are friction washers 32 and 33, the washer 33 fitting against the arm 24. Immediately below arm 24 is a fiber washer 35, and below that a metallic washer 36, and below that is a lock or spring washer 37 against which a nut 38 fits. By adjusting the nut 38 on bolt 23, a friction joint between members 24 and 14 is provided.

The rod 14 has an insulating block 40 secured thereon in which a metallic pin 41 is provided, and connected to this pin 41 is a wire 42 which leads to arm 25 and contact pin 26. A wire 45 is connected to pin 29 and leads back to fixed handle 43 mounted in the front board 12. A leaf spring contact member 44 is mounted on the inside surface of board 12, and is adapted to contact the metallic pin 41 when the rod 14 is slid forwardly or to the right in Figures 1, 2, and 4.

The pins 29 and 26 in normal position both bridge the slot 28, and when a coin is dropped therein, the pins and coin form a switch 50 to close the circuit from pin 41 to handle 43.

Mounted on base board 10 is a plurality of resistances such as electric light bulbs 60, 61, 62, 63, 64, 65, 66, 67, 68, 69, 70, and 71. A source of electrical energy is indicated at 51, which may be a storage battery, but preferably it is a 110 volt A. C. source of supply. One side of the electric wiring is indicated at 73 and the other side 30 is indicated at 76. The side 73 of the circuit leads to one side of resistances or bulbs 60, 61, and 62. Another wire 74 leads from the other side of resistances 60, 61, and 62 to one side of bulbs 65, 64, and 63 respectively. A wire 75 is connected to the other sides of bulbs 63, 64, and 65, and leads to leaf spring member 44. The wire 76 is connected to one side of resistances or bulbs 66, 69, 67, 70, 68, and 71 respectively. A wire 77 leads from the other side of resistance 45 or incandescent bulb 66 to leaf spring switch 20. Wire 78 leads from the other side of bulb 69 to leaf spring 21. Wire 79 leads from the other side of resistance 70, and is connected to leaf spring 19. Wire 80 leads from the other side of resistance or bulb 71, and is connected to the leaf spring switch member 18. Wire 81 leads from the other side of resistance 67 and is connected to leaf spring member 17, and wire 82 leads from the other side of resistance 68, and is connected 50 to leaf spring member 16.

Mounted on the base board 10 is a pin 85 against which the member 24 is adapted to rest when the parts are in normal position. The parts are held in normal position by means of a tension spring 88 which is anchored to the front wall 12 as at 87 and is anchored to post 23. The tension of this spring normally pulls the block 43 against the forward end of pipe 18, and holds the parts in the position shown in Figures 1, 2, and 4. In Figures 1 and 2, the apparatus is shown as a machine for imparting electrical shocks to a person and having the handles 14 and 42. In Figure 4, where a schematic wiring diagram is shown, the apparatus is shown as being capable of being used not only as an electro-therapeutic machine, but also as a circuit controller, and in this view instead of the rod 14 being pushed forward manually by the person receiving the shock, there is shown a pair of upstanding brackets 93 and 91 through which a threaded rod 92 is slidably passed, and between these brackets there is threadably mounted on threaded rod 92 a wheel 93, and the right-hand end of the threaded rod 92 is adapted to fit against the upright portion of handle member 14^a. A wire 94 is connected to handle 43 and passes to a resistance 95 which may be a suitable electrical resistance or rheostat or a house or building lighting circuit and from this resistance 95, a wire 96 is led to the rod 14.

Method of operation

With switches 98 and 100 open, let us assume that a coin is dropped into coin chute 28 and the operator seizes the upright portion of handle 14^a and the upright portion or left hand end of rod 14, squeezes same, and also places his other hand on the handle 43, and by a slight forward movement of rod 14, contact pin 41 is caused to engage leaf spring 44. In this position and before further right hand movement in Figures 1 and 2 is imparted to the rod 14, the current will pass through wire 73 and through incandescent bulbs or resistances 60, 61, and 62, and along wire 74 and through resistances 63, 64, and 65, and through wire 75 to leaf spring 44, and through pin 41 and through wire 42, switch 50, wire 45, and to handle 43, through wire 94, resistance 95, and wire 96. The resistance 95 which when used as an electro-therapeutic machine would be the human body. After passing through the resistance 95, the current will pass through rod 14, since block 43 is an insulation block, and will pass through post 22 and through all of leaf springs 16 to 21 inclusive, and through all of wires 77, 78, 76, 79, 80, 81, 82, through all of the resistances or incandescent bulbs 66 to 71, inclusive and back through wire 76 to the other side of the circuit. In this case, all of the resistances would be in the circuit, and a slight shock would be imparted to the man seizing the handles 14 and 43. It will be noted by referring to Figure 1 that the leaf springs 16 to 21 are curved at different points and have flat end portions of gradually increasing length progressing from spring 16 which has the shortest flat portion near its end to spring 21 which has the longest flat portion as is clearly shown in Figures 1 and 2. The ends of these flat portions are designated by break lines 16^a to 21^a. As the rod 14 is pressed forwardly or to the right in Figures 1 and 2, the post 22 will be shifted out of contact progressively one at a time with the leaf springs 16 to 21 respectively. As the rod passes out of contact with leaf spring 16, the resistance 68 will be disconnected, and as the rod moves further to the right in Figures 1, 2, and 4,

the leaf springs 17, 18, 19, 20, and 21 will progressively pass out of contact with the post 22, and therefore the resistances 67, 71, 70 and 66 will be disconnected from the circuit until finally only leaf spring 21 together with its resistance 69 will be in the circuit, and therefore, the only resistance in the circuit will be resistances 60 to 65 inclusive and resistance 69. If the person can stand this much voltage, he can then push the rod 14 further to the right, which will move the post 22 out of contact with the last or lowermost leaf spring 21, and this will completely disconnect the circuit and the operation will be completed. At this time, it will be observed that member 24 will have moved forward out of contact with the pin 85, and will be occupying a position at approximately right angles to the rod 14. And due to the friction joint between member 24 and rod 14, as rod 14 moves to the left under the pull of tension spring 88, when the operator releases the handle portion 14^a of rod 14, the pin 26 will be withdrawn from across the coin chute 28 as the rod moves backwardly, and this will allow the coin within the coin chute to fall into a coin box C, but when this occurs, the member 24 will strike pin 85, and as the rod 14 moves further to the left in Figures 1, 2, and 4, the pin 26 will be moved back to a position to bridge the coin slot 28, and ready for the reception of another coin for another user of the shocking machine. Of course, if this is not used for a shocking machine, but is used purely as a voltage regulator, then the coin slot mechanism would be dispensed with, and it would be a closed circuit at all times; that is, wires 42 and 45 would be permanently connected together.

The apparatus also has a wire 97 with a switch 98 therein connecting wires 75 and 76. There is also a wire 99 with a switch 100 connecting wire 74 to rod 14. It has already been described as to the paths of flow of the current with switches 98 and 100 open. With switches 98 and 100 closed, and before a coin is dropped into chute 28, and before an operator seizes the handle 43 and the handle portion 14^a, current will flow through wire 73, resistances 60, 61, 62, wire 74, resistances 63, 64, 65 and wire 76 back to the source. Wire 99, rod 14, post 22, leaf springs 16 to 21, wires 77 to 82, resistances 66 to 71 and wire 76 will also be in a parallel circuit, but only an infinitesimal amount of current will flow through resistances 66 to 71 as the line of least resistance will be through switch 98. When a coin is dropped into the chute, or with switch 50 closed, current will flow through wire 73, tubes 60, 61, and 62, wires 74 and 99, the rod 14, through contact leaf members 16 to 21 inclusive, and tubes 66 to 71 inclusive to a slight degree, but the bulk of the current will flow through resistances 63, 64, 65, and wires 97 and 76 back to the other side of the circuit. This is assuming that resistance 95 is not present. When resistance 95 is present either in the form of a circuit, or the human body, the current, when rod 14 is pushed forwardly to contact pin 41 with leaf spring 44, will then flow as follows:

Wire 73, incandescent bulbs 60 to 62 inclusive, wire 74, wire 99, rod 14, resistance 95 whether it be in the form of a human body, or a circuit, wire 45, switch 50, wire 42, leaf spring 44, wires 75, 97, and 76 back to the other side of the circuit. Some of the current will also be going through the rod 14, leaf spring contacts 16 to 21, and incandescent bulbs 66 to 71, due to the fact that resistance 95 as for example when it is in the form of a human body is great enough to cause

part of the current to flow through incandescent bulbs 66 to 71 as well as directly through resistances 63 to 65, and wires 67 and 76. As the handle is pushed inwardly, the leaf spring contact 16 to 21 inclusive will be progressively disconnected from post 22 thereby forcing more of the current through the resistance 95 until the point is reached where all of the incandescent bulbs 66 to 71 inclusive are disconnected from the circuit at which time maximum current will flow through resistance 95, and in this position, the course of the current will be wire 73, incandescent bulbs 60, 61, and 62, wire 74, wire 99, rod 14, resistance 95, wire 45, switch 50, wire 42, leaf spring 44, wires 75, 97, and 76. With the parts positioned as shown in the drawings, all bulbs are connected to the source 51. The dropping of a coin allows this current to flow to the handles 14 and 43.

It is preferable to operate the apparatus with switches 98 and 100 closed when it is used as a therapeutic machine for the reason that a cold incandescent bulb when current is first turned on to it will allow a much greater amount of electricity to pass through the filament, and will impart a much greater shock to the operator than a bulb having a hot filament. By having the switches 98 and 100 closed at all times, all of the bulbs will be energized to a greater or lesser degree, and thus when the operator seizes the handles 14 and 43, he will not get the intense shock he would otherwise.

In the drawings and specifications, there has been set forth a preferred embodiment of the invention, and although specific terms are employed, they are used in a generic and descriptive sense only and not for purposes of limitation, the scope of the invention being defined in the claims.

I claim:

1. In an electro-therapeutic machine, a framework, a front panel for the framework, a fixed handle in the front panel, a rod slidably mounted in the framework and front panel, and having a handle on the end thereof, a plurality of resistance members mounted in the framework, an electrical circuit connected to said resistances, a post rising from said rod, a plurality of leaf spring contacts engaging said post, some of the resistances being connected on one side to said leaf spring contacts, said circuit leading through said resistances and through a resistance connected to the said handles, said leaf spring contacts having flat portions of various lengths for contacting said post whereby when said rod is slid relative to the leaf spring contacts, the resistances connected to said leaf spring contacts will be disconnected, one at a time, from the circuit.

2. In an electro-therapeutic machine, a framework, a fixed handle on the framework, a rod slidably mounted in the framework, and having a handle portion on one end thereof, the two handles being adapted to be engaged by a person to form a resistance therebetween, an electrical resistance mounted in the framework and having one side connected to one side of a source of electrical energy and having its other side connected to said rod and forming an electrical circuit, and having a plurality of other resistances having one side thereof connected at the other side of the source of electrical energy, and having their other sides releasably connected to said rod whereby when the rod is slid forwardly in the framework, the said other resistances will be disconnected, one at a time, from the circuit.

3. In an electro-therapeutic machine, a frame-

work, a front panel for the framework, a fixed handle in the front panel, a rod slidably mounted in the framework and front panel, and having a handle on the end thereof, a plurality of resistance members mounted in the framework, an electrical circuit connected to said resistances, a post rising from said rod, a plurality of leaf spring contacts engaging said post, some of the resistances being connected on one side to said leaf spring contacts, said circuit leading through said resistances and being adapted to include a patient in contact with said handles, said leaf spring contacts having flat portions of various lengths for contacting said post whereby when said rod is slid relative to the leaf spring contacts, the resistances connected to said leaf spring contacts will be disconnected, one at a time, from the circuit, a coin controlled switch disposed between one side of said circuit and said fixed handle, said rod having an arm pivotally mounted thereon, friction means for delaying movement of said arm on its pivot, a pin on said arm forming a part of said coin-controlled switch, and a stop on said framework for engaging said arm and causing the same to pivot on the rod as the rod returns to normal position to move the pin on the arm into position to close the circuit when a coin is inserted in the coin controlled switch.

4. A voltage regulator comprising a framework, a fixed handle on the framework, a metallic rod slidably mounted in the framework and having a handle thereon disposed on the exterior of the framework, both of said handles being adapted to have a suitable resistance connected thereto, a post integral with said handle, a plurality of leaf spring contacts mounted in the framework and having end portions of different lengths for engaging said post, an insulation block mounted on said rod and having a metallic pin therein, a leaf spring member mounted in the framework, and being adapted to engage said pin when the rod is slid forwardly in the framework, a source of electrical energy, a second resistance having one side thereof connected to one side of said source, the other side of the resistance being connected to said rod, a connection between said pin and said fixed handle, whereby when the rod is slid forwardly the circuit will be established through the resistance between the handles and through said second resistance, a third resistance in said framework having one side thereof connected to the said one side of the source of electrical energy, a connection between the other side of said third resistance and said leaf spring member mounted in the framework, a plurality of other resistances having one side thereof connected to said other side of said source of electrical energy, the other sides of the plurality of said resistances being connected to said leaf spring contact members contacting the post integral with said rod, whereby a circuit will be established through all of said resistances, and through the resistance between the handle members, and when the rod is slid forwardly, the leaf spring members will gradually, one at a time, be disconnected from said post by the post sliding out of contact excessively with the straight end portions, to thereby disconnect said other resistances, one at a time, to cause a greater voltage in the circuit passing through the second and third resistances, and through the resistance between the handle members.

5. A voltage regulator comprising a framework, a fixed handle on the framework, a metallic rod

slidably mounted in the framework, and having a handle thereon disposed on the exterior of the framework, both of said handles being adapted to have a suitable resistance connected thereto, a post integral with said handle, a plurality of leaf spring contacts mounted in the framework and having their free end portions of varying lengths for engaging said post, an insulation block mounted on said rod and having a metallic pin therein, a leaf spring member mounted in the framework and being adapted to engage said pin when the rod is slid forwardly in the framework, a source of electrical energy, a second resistance having one side thereof connected to one side of said source, the other side of the second resistance being connected to said rod, a connection between said pin and said fixed handle, whereby when the rod is slid forwardly the circuit will be established through the resistance between the handles and through said second resistance, a third resistance in said framework having one side thereof connected to the said one side of the source of electrical energy, a connection between the other side of said third resistance and said leaf spring member mounted in the framework, a plurality of other resistances mounted in the framework having one side thereof connected to the said other side of said source of electrical energy, the other sides of the plurality of said resistances being connected to said leaf spring contact members contacting the post integral with said rod, whereby a circuit will be

5 established through all of said resistances, and through the first resistance disposed between the handle members and when the rod is slid forwardly, the leaf spring members will gradually, one at a time, be disconnected from said post, to thereby disconnect said other resistances, one at a time, to cause a greater voltage in the first and second resistances, and the resistance between the handle members, and a coin controlled switch in the circuit leading from the pin in the insulation block to the said fixed handle.
